UNITED STATES PATENT OFFICE.

ANNA M. KNOOP, OF NEW YORK, N. Y.

CROCHET HAT, CAP, &c.

SPECIFICATION forming part of Letters Patent No. 246,151, dated August 23, 1881.

Application filed April 20, 1881. (Model.)

To all whom it may concern:

Be it known that I, ANNA M. KNOOP, of the city, county, and State of New York, have invented new and Improved Crochet Goods, of which the following is a specification.

The object of my invention is to provide new and improved crochet goods, which can be used as hat-frames, book-satchels, sewing-baskets, &c.

10 The invention consists in an article of crochet-work which is stiffened by means of glue, gelatine, or similar substance, is then dried on a mold, which gives it the desired form, and is then protected with a suitable varnish.

15 In the accompanying drawing a perspective view of a hat-frame made of improved crochet goods is shown.

A crocheted article is made of cotton or other thread in the ordinary manner and of any desired pattern, this article being formed according to the purpose for which it is to be used—for instance, as a hat-frame, a satchel for school-books, sewing-basket, card-basket, &c. This crocheted article is then dyed any desired color, 20 preferably yellow, to resemble straw. The article is then immersed in or impregnated with dissolved glue, gelatine, starch, or suitable stiffening material. The crocheted glued article is then placed on a mold, and as this glue or stiffening material dries and hardens it causes the crocheted article to assume and retain the shape of the mold. The dried article is then varnished with shellac or other suitable varnish, to prevent moisture from acting 25 upon the stiffening material. If the crocheted

article is to be used as a hat-frame it is attached to a wire frame, provided with a lining, &c.; and if it is to be used as a school-book satchel or basket it is trimmed with ribbons and provided with handles in the ordinary 40 manner.

In defining my invention more clearly I would state that I am aware that close fabrics and hat-bodies have been made water-proof by means of a varnish, and I do not claim this 45 broadly. I do not know, however, that crochet-work has ever been utilized for hats and other articles, as described; and the stiffening and varnishing have a special value in this case. They do not serve to make a close, tight, and wa- 50 ter-proof surface, as has been heretofore done; but the stiffening serves to cement and hold the figures of the crochet-work in their proper symmetrical relation to each other, so as to preserve always the shape and beauty of the 55 figures, while the varnish maintains this relation and prevents the stiffening from softening and deteriorating by absorbed moisture.

Having thus described my invention, I claim as new and desire to secure by Letters Patent— 60

A hat or its equivalent, as described, made of open crochet figures maintained in symmetrical relation by a stiffening and protected by a superficial coat of varnish, as and for the purpose described.

ANNA M. KNOOP.
